UNITED STATES PATENT OFFICE

139,755

DESIGN FOR A SWITCH HOUSING

Phillip A. Celander, Freeport, Ill., assignor to First Industrial Corporation, Wilmington, Del., a corporation of Delaware

Application September 28, 1944, Serial No. 115,502

Term of patent 7 years

(Cl. D26—13)

To all whom it may concern:

Be it known that I, Phillip A. Celander, a citizen of the United States, residing at Freeport, in the county of Stephenson and State of Illinois, have invented a new, original, and ornamental Design for a Switch Housing, of which the following is a specification, reference being had to the accompanying drawing, forming part thereof.

In the drawing:

Figure 1 is a side perspective view of a switch housing embodying my new design;

Fig. 2 is a top view;
Fig. 3 is a side elevation showing the side opposite that of Figure 1, and

Fig. 4 is an end elevation showing the end opposite that of Figure 1.

The dominant features of my design reside in the portions shown in full lines.

I claim:

The ornamental design for a switch housing, substantially as shown and described.

PHILLIP A. CELANDER.
